CLAIM

The ornamental design for a fiber optic closure with surface ornamentation, as shown and described.

DESCRIPTION

FIG. 1 is a front perspective view of a fiber optic closure with surface ornamentation illustrating our new design;

FIG. 2 is a top view thereof;

FIG. 3 is a bottom view thereof;

FIG. 4 is a left view thereof;

FIG. 5 is a right view thereof;

FIG. 6 is a front view thereof; and,

FIG. 7 is a rear view thereof.

The broken lines immediately adjacent the surface ornamentation represent the bounds of the claimed design while all other broken lines are directed to the environment, which form no part of the claimed design.
